UNITED STATES PATENT OFFICE.

FREDERICK FRANCIS FECHER, OF ROCKVILLE CENTER, THEODORE DANHEISER, OF NEW YORK, AND RICHARD BALDAUF, OF HEMPSTEAD, NEW YORK, ASSIGNORS TO THE BECK DUPLICATOR COMPANY, A CORPORATION OF NEW YORK.

DUPLICATOR.

Application filed April 12, 1924. Serial No. 706,026.

This invention relates to that type of duplicator in which a negative or reversed impression of the matter to be copied is impressed upon a gelatinous duplicating surface or the like and positive impressions taken therefrom by bringing sheets of paper or the like successively into contact therewith.

The invention consists in the novel construction, arrangement and combination of various devices, elements and parts, as set forth in the claims hereof, one embodiment of the same being illustrated in the accompanying drawings and described in this specification.

In the accompanying drawings,

Fig. 1 is a side view of a duplicator embodying our invention;

Fig. 2 is a longitudinal vertical section;

Fig. 3 is a plan view;

Fig. 4 is an end view; and

Fig. 5 is a perspective view of the stick or spindle upon which the duplicator film may be wound.

In carrying our invention into effect in the embodiment thereof which we have selected for description in this specification and illustration in the accompanying drawings, we provide a duplicator, the frame of which may be of any suitable type, such as for instance comprising frame members 12, in which are journaled rollers 13 upon which an adhesive duplicating film 14 is adapted to be wound. The film 14 passes upward and over a bed 16 secured between the members 12, rollers 15 adjacent the ends of the bed being adapted to prevent the film from scraping against the said ends when the rollers 13 are rotated.

One of the rollers 13 forming part of our invention is shown in perspective in Fig. 5. It comprises a body portion, around which the film is wound, and a lug 20 at each end adapted to constitute a chuck-engaging journal.

The rollers are operatively connected with the frame as follows: Near each end of the side frame 12 on the left of the machine is provided a shaft 10 (see Fig. 4) rotatably mounted in said frame, the inner ends of which are provided with grooves adapted to receive the lugs 20 of the rollers. The inner ends of the shafts 10 project laterally

inside of the inner wall of the side frame and are surrounded by annular walls 70 (see Fig. 4). To these shafts are secured operating cranks 17 and ratchets 18, and pivoted on the frame are pawls 19.

On the other of said side frames are provided devices for removably engaging the other ends of the rollers 13. These devices consist of rotatable shafts 65 journaled in the side frame 12 on the right of the machine. These shafts 65 are provided with grooves analogous to those in the shafts 10, and which are also adapted to receive the lugs 20 of the rollers. The shafts 65 are provided at their outer ends with counterweights 66 so adjusted that when the shaft and counterweight lie free, that is, disengaged from the roller 13, the groove will lie approximately in a horizontal position. The inner ends of the shafts 65 are surrounded, except for small openings towards the ends of the machine, by broken annular walls 67, the open spaces left in these walls being normally closed by double-angled levers 68 pivoted to the inside of the side frame at 69 (see Fig. 2). A spring 168 is provided which tends to hold each lever 68 in its raised position, as shown in Fig. 2.

In order to place the roller 13 in the machine, the lug at one end is inserted in the groove in the inner end of the shaft 10, and the same is thereupon held in position by the annular wall 70. The lever 68 on the other side of the machine is then depressed, which permits the lug 20 on the other end of the roller to be inserted in the groove in the inner end of the shaft 65. The lever 68 is then raised and the roller will be then held securely in position and yet perfectly free to rotate.

It is obvious that by means of the construction above described either end of the roller may be journaled in either side of the machine and that accordingly a pair of such rollers, bearing a duplicating band, may be taken from the machine, the rollers reversed end for end and the band turned in the direction the reverse of its former direction, and the rollers again inserted in the machine, but at opposite ends from those in which they were previously journaled.

In connection with the lower part of the structure above described, we provide a

paper-support or table member having sides 21, a front end 22, and a bottom 23 covering the greater part of the area, but having an open portion at one end. This table is provided at each side near the rear end with downwardly extending lugs 24, the lower ends of said lugs being rigidly secured to a rod 25 journaled in the side members 12. A spring 26 is provided, which tends to normally raise the table into its elevated position, as shown in dotted lines in the drawings. This spring is coiled around the rod 25, one end of the spring being passed through a perforation 40 and the other end 15 of said spring being placed so as to bear down upon a stop consisting of a bar 41 extending transversely of the frame.

Slidably mounted upon the table is a paper stop 30 adapted to bear against the 20 ends of sheets of paper laid upon said table, and similar stops 31 adapted to bear against the sides of such sheets. All of these stops are adjustable, whereby the table is adapted to receive sheets of paper of various different sizes.

Near the front end of the table and projecting over the open space left in the same, is a bar 35. This bar is supported at its ends by resilient arms 36, secured to the floor 30 of the table.

Located on the right hand side of the machine (best shown in Fig. 3) secured in brackets 50 is a rod 51. Slidably mounted on this rod is a frame 52 having a lateral 35 extension 53 in which is journaled a roller 54. A handle 55 is provided in the extension 53 to facilitate the manipulation thereof. This frame and roller when in operative position lie horizontally as shown in Figs. 1, 40 3 and 4, but may be swung out of the way into a vertical position as shown in part in Fig. 2. The roller 54 is adapted to roll over the bed of the machine during the greater part of its course, but at the forward end 45 of its path the ends of the roller run upon slightly elevated tracks 46 (see Fig. 1).

In the rear end of the frame 52 is a socket, the upper wall of which is designated 61 (see Fig. 1). This socket is adapted to 50 engage with a pin 62 on the side 21 of the paper-table, when the frame is in the position shown in full lines in Fig. 1 and thereby hold the paper-table in its lowered position against the action of the spring 26 when 55 the machine is not in use. When it is desired to operate the paper-table, the frame 52 and connected parts are drawn backward into the position shown in dotted lines in Fig. 1, thus releasing the forward end of 60 the paper-table and allowing it to spring upward into the position shown in dotted lines in Fig. 1.

The operation of our invention is as follows: Upon the table is placed, face downward, a sheet of paper bearing the matter

which it is desired to duplicate or copy, the same being written or printed with so-called hectographing ink, and upon this is placed any desired number of sheets of blank paper upon which it is desired to copy the matter transferred from the original to the duplicating medium, so that one end of each of said sheets of paper shall rest against the lower end 22 of the table and the side edges of said sheets shall rest against the stops 31, and the other end of said sheets shall rest against the stop 30, it being understood that the stops 30 and 31 are adjusted so as to permit the sheets of paper to easily lie between them. If it is desired to use paper of the same size as the table, the adjustable stops 30 and 31 may of course be removed. It will be understood that the ends of the sheets of paper lie over the opening in the floor of the table member, and that after the paper is placed in position the bar 35 is swung into position over the ends of the sheets of paper. The original and the blank sheets of paper being thus in place upon the table, the pile of paper may if desired be steadied by placing the hand upon the same, although ordinarily this will not be necessary. It is to be understood that the table is normally in its lowered position as shown in Fig. 1. The bar 35 is then depressed, the effect of this being to bring a portion of the lowest sheet of paper in the pile, that is, in this case, the original matter to be duplicated, into contact with the adhesive duplicating medium to which it will adhere. The table being then 100 swung upward, this sheet of paper will be dragged out from under the pile. The table being then maintained by the spring 26 in a raised position, pressure may be applied to the sheet of paper then on the duplicating medium, which is done by passing the roller 54 backward over the paper, the same being guided by the rod 51. When the roller 54 is moved forward again, into the position shown in Fig. 1, (it then resting upon the 110 elevated trackways 46) the sheet of paper containing the original matter is then stripped off, the table caused to assume its lowered position, and the operation repeated with the blank sheets of paper until as many 115 copies as are desired have been made, whereupon a new portion of the duplicating medium may be brought into play, so that when desired a new impression may be transferred thereto and copies made from the new impression in the manner described. In Fig. 1 of the drawings 60 represents a sheet of paper which has been placed upon the paper-table, and the end of which has been depressed so that it has adhered to the duplicating band 14. The drawing shows the position of the paper just before the table begins its upward swing. It will be clear from an examination of this Fig. 1 that as the table rises up, the sheet of paper 60 will be 130

drawn off from the table, and out from underneath any other sheets of paper which may be piled thereupon, and that when the table has finally risen into the position shown in dotted lines in Fig. 1, the sheet of paper will lie flat upon the duplicating band 14, ready to be passed over by the roller 54.

We do not limit ourselves to the particular construction hereinabove described, as it is obvious that various modifications of the same may be made without departing from the spirit and scope of the invention.

The advantages of the invention will be obvious from what has been above said with regard to its construction and operation.

Having thus described our invention, what we claim as new and desire to secure by Letters Patent is as follows:

1. The combination with a pair of frames and a spindle provided at each end with a chuck-engaging lug, of means adapted to journal said spindle in said frames, comprising a shaft rotatably mounted in each frame provided with a socket adapted to receive a lug of said spindle, and retaining means on one of said frames adapted to secure an end of said spindle in said journal, comprising a broken annular wall and a lever pivotally attached to said frame adapted when in one position to avoid the break in said wall and to allow the end of a spindle to be inserted in or removed from the adjacent rotatably mounted shaft, and when in another position

to close the break in said wall and hold the end of the spindle therein.

2. The combination with a pair of frames and a spindle provided at each end with a chuck-engaging lug, of means adapted to journal said spindle in said frames, comprising a shaft rotatably mounted in each frame provided with a socket adapted to receive a lug of said spindle, and retaining means on one of said frames adapted to secure an end of said spindle in said journal, comprising a broken annular wall and a lever pivotally attached to said frame adapted when in one position to avoid the break in said wall and to allow the end of a spindle to be inserted in or removed from the adjacent rotatably mounted shaft, and when in another position to close the break in said wall and hold the end of the spindle therein: said last mentioned rotatably mounted shaft being provided with a counterweight adapted to normally hold the shaft so that the slot therein shall be in a predetermined position to facilitate the insertion therein of an end of said spindle.

In witness whereof we have hereunto signed our names the said DANHEISER and BALDAUF this 7th day of March, 1924, and said FECHER this 11th day of April, 1924.

FREDERICK FRANCIS FECHER.
THEODORE DANHEISER.
